UNITED STATES PATENT OFFICE.

THOMAS W. GREEN, OF TRENTON, NEW JERSEY.

MULTISTAGE CENTRIFUGAL BLOWER.

1,350,724.

Specification of Letters Patent. Patented Aug. 24, 1920.

Application filed August 9, 1918. Serial No. 249,079.

To all whom it may concern:

Be it known that I, THOMAS W. GREEN, a citizen of the United States, residing at 219 Bellevue avenue, Trenton, in the county of

5 Mercer and State of New Jersey, have invented a certain new and useful Multistage Centrifugal Blower, of which the following is a specification:

My invention relates to centrifugal pumps, 10 blowers or exhausters for air, gas and other fluids intended to increase the pressure by successive compressions in different stages or compartments through which the fluid passes in series.

15 My main purpose is to increase the area of the ports by which the fluid passes into the compartments.

A further purpose is to provide a plurality of vanes in the rotor for each inlet 20 port in the stator.

A further purpose is to use inlet ports having circumferential widths considerably in excess of the distance between adjoining vane edges.

25 A further purpose is to supply end inlets for one or more of the sets of vanes used.

A further purpose is to stage axially as well as radially.

A further purpose is to stiffen the vanes.

30 A further purpose is to adapt the construction to the use of cast forms and rolled or pressed sheet metal connections.

My invention relates both to the processes involved and to apparatus by which the 35 processes may be carried out.

Further purposes will appear in the specification and in the claims.

I have preferred to illustrate my invention by but two forms thereof, selecting 40 forms which are practical, efficient and thoroughly reliable and which at the same time well illustrate the principles of my invention.

Figure 1 is a longitudinal section corresponding to line 1—1 of Fig. 5 of a preferred form of my invention.

Fig. 2 is a fragmentary section upon line 2—2 of Fig. 1.

Figs. 3 and 4 are perspective views of 50 differing forms of vane which may be used in my invention.

Fig. 5 is a section upon line 5—5 of Fig. 1.

Fig. 6 is a fragmentary section showing 55 a portion of Fig. 5 with the parts in different relative positions.

Fig. 7 is a top plan view of one of the cylindrical partitions of the stator.

Fig. 8 is a section upon line 8—8 of Fig. 9 showing a modified form. 60

Fig. 9 is a section upon line 9—9 of Fig. 8.

Fig. 10 is a fragmentary section corresponding generally to Fig. 9, but showing a different construction of vane. 65

Fig. 11 is a section corresponding generally to Fig. 8, but showing a single stage mechanism which may be multistaged on the opposite side, if desired.

In the drawings similar numerals indicate corresponding parts. 70

Though I recognize that my invention is applicable to various pumping, blowing and exhausting uses in the handling of air, gas, water and many other fluids, both gaseous and fluid, and intend to cover such varied applications herein, it is inconvenient to make the references to the function and the fluid general where they occur, and I will therefore, as a matter of convenience, describe the invention in terms of air blowers, 80 but without intention to limit the invention thereto.

In the operation of multistage blowers the total capacity has been limited by restriction of the size of the ports through the 85 fixed cylindrical partitions of the stator, and the partitions themselves have been unduly limited by structural conditions reducing the extent of fluid flow and the capacities of the individual compartments handling the 90 air.

I have undertaken to improve the inlet openings both by end inlets and by increasing the number of vanes (and correspondingly the number of pockets or compartments) per inlet opening, with a view to permitting larger radially-extending ports and better sealing functions. I have also provided for a larger use of pressed or rolled metal, permitting the more general 100 use of this thinner and lighter metal, instead of the cast metal from which the construction would otherwise be made.

Considering first the form in Figs. 1—7, and viewing it as an illustration merely:— 105 the outer casing or frame is made up of two spaced ends 15, 16 united by a nearly cylindrical central cover 17. The casing may be divided in any way which convenience suggests to facilitate quick assemblage 110 of the mechanism.

The rotor is mounted upon a shaft 18

which is supported in any suitable bearings and which carries a hub 19 and spider 20.

The vanes are mounted on opposite sides of the spider in circumferentially arranged sets or groups and are spaced from each other by the cylindrical, inwardly-directed partitions of the stator.

In Fig. 1 four sets of vanes are shown on each side, indicated at 21, 22, 23 and 24 on the one side; and 25, 26, 27 and 28 on the other side.

Their preferred angles with the radii of the rotor are seen in Figs. 5, 6, 8 and 11.

Between these sets of vanes the cylindrical partitions from the stator project from opposite sides at 29, 30 and 31 from the one end and 32, 33 and 34 from the other end with continuous stator partitions from end to end at 35.

20 The inner vanes 21 and 25 are merely angularly placed blower blades which are secured upon diagonal faces 36 of the hub and perform no other function than to sweep the air through the ports 37 of the partitions 29 or 32, so that it may successively be forced through any desired number of ports 38, 39 and 40 of partitions or cylinders of successively increasing diameter.

25 The vanes 22 and 26 are of the type shown in Fig. 3, comprising bodies 41, extending at an angle to the radius as seen in such figures as 5 and 6, and circumferentially-extending ends 42 and 43, the ends 42 being shortened to provide for admission of air at the ends *i. e.*, between them and the center. The ends 42 of adjoining vanes are secured in such manner as to overlap, each one supporting the adjoining one, as best seen in Fig. 2, while the ends 43 are separately secured to the spider to hold the entire vane. In this manner the vanes and their ends form the sides and ends of boxes which are without either tops or bottoms and which are completed by the cylindrical fixed partitions 29, 30 and 32, 33.

30 In the case of the outer sets of vanes, inlet of air at the end is not intended and the ends are full, as seen at 44 in Fig. 4, corresponding to the form of vane having body 41', seen at 23, 24, 27 and 28. These also overlap at their outer ends, farthest from the spider, as seen in Fig. 1, and are united separately to the spider by any suitable fastenings at their inner ends.

35 This forms a convenient and desirable method of support of vanes to permit the use of pressed metal and affords a maximum of stiffening.

40 I show a desirable form of mounting for the stator partitions 2' -35, forming circular axially-extending flanges upon the end pieces, or rigidly supported with respect to them, and fastening the partitions to these flanges at intervals. The flanges thus continuously support the partitions upon either

the inner or outer side (radially) thereof and may be secured to them at any desired intervals to stiffen them, permitting the use of cylindrically bent thin sheet metal for this purpose.

70 The outer partitions 31, 34 and 35 are shown as supported by flanges 45, 46, 45', 46', integral with the casing and by common fastening means which can be passed conveniently through both. The partitions 30 and 33 engage flanges 47, 47', also integral with the casings. For convenience in manufacture and assemblage the supporting structure radially inside of this point is separated from the rest of the heads and is fastened to the same flanges but upon opposite sides of the partitions. The inner supporting structure comprises outer flanges 48, 48', inwardly extending web ends 49, 49' and rings 50, 50'. The flanges 48, 48' are bolted 80 to flanges 47, 47'. Within the ends, I form a series of ports 51, 51' and the rings are used for the support of the partitions 29 and 32.

85 The air passes into the casings at both ends through openings 52, 52', into spaces 53, 53' from which it distributes through the center along the shaft to the ports 37. These ports and ports 51 open into compartments of the same set and, being placed in 90 approximately the same planes, considered with respect to the changing angular positions occupied by the compartments, fill the same compartments concurrently or nearly so. There is one difference; that the air is 100 driven through the ports 37 by reason of the belt or motor-driven rotor through vanes 21 or 25, whereas the air flows freely through ports 51, 51'.

95 This gives a very large volume of air inlet into the particular compartments 54 which are opposite the ports at the time, with successive movements of the air into compartments 55 and 56, as the rotor turns.

100 The air is successively driven through ports 38, 39 and 40 and finally emerges into an outer circumferentially-extending compartment 57 by which it is conducted to the air receiver or storage through one or more openings 58.

110 One of the features of my invention is to provide an extent of opening into the compartments, measured in a circumferential direction, considerably in excess of the thickness of the adjoining inner and outer 120 vanes so that these vanes will not close the openings (ports) at any time during their passage across the openings. This is made possible by the relatively large number of vanes which I supply per port, so that there 125 are a plurality, preferably two or more compartments closed on the inside at one time, while a third compartment is being filled from the interior through a large port opening.

Likewise preferably two or more adjoining compartments are closed on the outside while the intervening compartments (between these successive sets of two or more closed compartments) are discharging through large ports into outside compartments. Here again the port is preferably much wider, circumferentially than the outer and inner surfaces (thickness) of the vanes which wall the compartments, so that the ports are never fully closed by either the outer or inner adjoining vane surfaces. The combination between the multiplicity of compartments and the wide opening makes the wide opening of the ports and the end-opening ports permissible and effective.

In the position shown in Fig. 5, the rotor is moving in counter clockwise direction. The compartments 54' have been receiving air from the interior space about the hub and end ports 51' and are soon to be cut off, whereas the compartments 54" are just beginning to receive air through the ports 37 and the end ports. At the same time the compartments 54" are expelling air through the ports 38 into compartments 55', other similar compartments 55" are sealed both inside and outside and compartments 55" are expelling air to compartments 56" through ports 39 and still other compartments 55" have just expelled their air. Compartments 56" are expelling air finally into the space 57 through ports 40 and the other compartments of this set are either approaching the discharge point or have discharged.

The section shown in Fig. 6 shows a slightly advanced position which the rotor assumes with respect to the ports and in which the compartment 54' is now receiving air to its fullest extent through the ports 37 and 51, the ports 54" are discharging into compartments 55' and compartments 56" are discharging air through ports 40.

Though the end ports 51 do not have the pressure of diagonal blades 21 and 25, to force the air through them into the compartments and for this reason are not quite as effective for their area of surface as the ports 37 in filling the compartments 54, they open into the inner part of the compartments (the part of smallest diameter) and provide considerable flow due to suction because of the slope of the vanes.

The ports which are considered radial, to distinguish from the end ports, are preferably at an angle to the radii.

In the form shown in Figs. 8-10 the same general arrangement of successively increasing stages of vanes is used, but the two sides have separate outlets instead of fitting into a common outlet. The outlet from one side supplies the inlet air to the other, thus increasing the compression of a smaller volume of air. There are also some differences in the points at which the air is received

and discharged from the casing, in the manner in which the vanes are supported, and in the vanes themselves.

The air inlet 52" is at the top and the air at atmospheric pressure enters the space about the shaft at one end only, passing through the successive radial and end ports into compartments corresponding with those in Figs. 1 and 5. The partitions 29', 30', 31' and 35' are secured directly to flanges upon the inside of the casing and the vanes are open-ended, sealing on the inside against strips 59, 59', 59" 70

The air is expelled from the stages at the left end of the figure into an outer compartment 57' from which it passes through a passage 60, to an inlet 52" at the right hand side of the figure and begins a series of further compressions here, in successive stages from the inside outwardly. There are but two series of compartments at the right hand side in the illustration, on account of the smaller diameter remaining inside the passage 60. These two compartments are constructed in the same general manner as those upon the left and discharge into an outer channel 57" whence the air is passed out through a discharge opening 58'.

In Fig. 11 a single stage type is shown, such as might be used separately for special purposes or, in a smaller construction, as one stage of a multi-stage blower of the general character shown in Fig. 9. This shows the adaptability of a construction of 100 the general character of Fig. 9, to use with ports in the ends of the compartments through the stator.

In these later forms as in the form shown in Figs. 1-6, the air passes into the first set 105 of compartments through wide ports and is relatively compressed in that compartment with respect to the entering air by reason of the angular position of the vanes forming the compartment. With progress of the rotor the inner ends of the successive compartments are closed before the outer ends of the compartments come in line with the discharge openings. This gives an effective seal, preventing leakage of the air inwardly. Where there are outside sets of compartments the air from the inner compartments, sealed as described, is forced into the outer set through large ports opening when the compartments have been moved forward into line with the ports and the operation is repeated. From the outside set of compartments the air is discharged into the passage 57, 57', or 57" by which it is led out to the receiver or to another 120 series of compartments for further compression as preferred.

It will be obvious that my invention may be applied to a great variety of other structures and with other means while still se- 130

curing at least a part of the benefits of the combinations and structure invented by me.

Having thus described my invention, what I claim as new and desire to secure by Letters Patent is:

1. In a centrifugal fluid pump, a pair of coaxial, cylindrical fixed partitions of different diameter having ports out of line radially, in combination with a rotor having 10 vanes at an angle to the radii, the inner and outer surfaces of the vanes, considered radially, being of smaller circumferential extent than the ports so that they are incapable of covering the edges of adjoining port openings and bearings for the rotor.

2. In a centrifugal fluid pump, a stator having coaxial cylindrical partitions of different diameter and end walls therefor, the partitions being ported out of line radially in the two partitions, in combination with a rotor, bearings therefor, a plurality of vanes at an angle to the radii carried by the rotor and extending circumferentially at their outer and inner limits less than the circumferential extent of the ports respectively and vanes carried by the rotor tending to force the air through the inner ports.

3. In a fluid pump, a stator, a pair of coaxial, cylindrical partitions therefor having 30 ports out of line radially and an end wall having ports approximately corresponding in angular position with the ports in the inner partitions, in combination with a rotor, bearings therefor, vanes upon the rotor at an angle to the radius fitting between the partitions and having less circumferential extent at the inner and outer edges than the ports in the adjoining partitions.

4. In a fluid pump, a stator, a pair of coaxial, cylindrical partitions therefor having 40 ports out of line radially, an end wall having ports in angular position approximately corresponding with the ports in the inner partitions, in combination with a rotor, vanes upon the rotor at an angle to the radius fitting between the partitions and having less circumferential extent at the inner and outer edges than the ports in the adjoining partitions and means carried by 50 the rotor for forcing air through the inner partitions.

5. In a fluid pump, a stator, a pair of coaxial, cylindrical partitions carried thereby, the outer partition being ported, an end 60 wall at one end of the space between the partitions, ports at intervals in the end wall, a rotor, bearings therefor and vanes carried by the rotor between the two partitions.

6. In a fluid pump, a stator, a pair of coaxial, cylindrical partitions carried thereby, the outer partition being ported, an end wall at one end of the space between the partitions, ports at intervals in the end wall, a rotor, bearings therefor, and vanes carried 70 by the rotor between the two partitions and

having circumferential extent at the end less than the port in the end wall.

7. In a multistage fluid pump, a stator, an outer casing therefor, a plurality of coaxial, cylindrical spaced partitions having ports 70 out of line radially, in adjoining partitions and end walls between the partitions, in combination with a rotor, bearings therefor and vanes carried by the rotor lying between the successive pairs of partitions and having 75 less circumferential extent at the inner and outer edges than the ports in the adjoining partitions.

8. In a fluid pump, a stator, a pair of coaxial, cylindrical partitions attached thereto, ported out of line radially, in combination with a rotor, bearings therefor and vanes carried by the rotor in number exceeding twice the number of ports in the partitions and having less circumferential 80 extent at the inner and outer edges than the ports in the adjoining partitions.

9. In a multistage fluid pump, a stator, a plurality of coaxial cylindrical partitions carried thereby having ports out of line in 90 adjoining partitions radially and end walls for the spaces between the partitions, the end walls between the innermost pair of partitions being ported and those between partitions farther out from the axis being 95 without ports.

10. A multistage fluid pump comprising two sets of coaxial cylindrical fixed partitions having ports out of line radially between adjoining partitions and occupying a small part only of the circumference, a rotor 100 lying between the two sets, bearings for the rotor, oppositely directed vanes on the rotor lying between the partitions and having circumferential extent less than the ports in 105 the adjoining partitions in combination with walls directing the discharge from one set of partitions and vanes into the inner spaces of the other set of partitions and vanes.

11. In a multi-stage fluid pump, a stator having a series of coaxial, cylindrical partitions ported at intervals, the ports in adjoining partitions being out of line radially, in combination with a rotor having a series 110 of sets of vanes, one set between each adjoining two partitions and exceeding in number twice the number of the ports, the circumferential extents of the inner and outer effective vane edges, crossing the ports being less than the circumferential extent of 120 the ports in the adjoining partitions so that the ports are never closed.

12. In a multi-stage fluid pump, a stator comprising ends and a central casing section uniting the ends, a rotor having bearing 125 in the stator, a spider on the rotor and a plurality of blades mounted upon the spider, a plurality of coaxial, cylindrical partitions supported by the stator and having ports therethrough at intervals, the ports of ad- 130

- joining partitions being radially out of line, a series of blades supported upon the rotor between each pair of partitions and in number more than twice the number of the ports 5 in the adjoining partitions and end ports in the end walls for one of the series of vanes.
13. In a multistage fluid pump, a stator having an end wall, interior circular flanges 10 thereon and separate, spaced, cylindrical partitions rigidly secured to said flanges.
14. In a multistage fluid pump, a stator comprising opposite end walls and having inwardly-directed coaxial cylindrical flanges 15 thereon, in combination with separate, spaced, inwardly directed partitions fitting the flanges and secured thereto.
15. In a multistage fluid pump, a stator comprising opposite end walls and axially 20 directed, coaxial, cylindrical flanges thereon in combination with inwardly directed partitions fitting the flanges and secured thereto, one of the partitions extending across from a flange on one end to a flange on the 25 other end.
16. In a multistage fluid pump, a stator having circumferentially-extending, axially-directed flanges in combination with separate, spaced, cylindrical partitions secured 30 thereto and an end wall secured to one of the flanges.
17. In a rotary fluid pump, a rotor spider in combination with vanes carried thereby, flanges on the vanes at their inner ends secured 35 to the spider and flanges on the outer ends of the vanes overlapping to stiffen one vane by securing it to the next adjoining vane.
18. In a rotary fluid pump, a rotor vane 40 comprising a blade adapted to lie at an angle to the radius and oppositely-directed flanges for attachment respectively to a rotor spider and to the next adjoining vane.
19. In a rotary fluid pump, a rotor vane 45 comprising a blade and oppositely-directed flanges, one flange adapted to be attached to the rotor and the other of partial axial length adapted to engage the next vane and relieved to permit air inlet through the end 50 inside the flange.
20. A rotor, a vane having a flange for attachment thereto and a flange at the opposite end thereof occupying less than the entire radial extent of the vane, in combination 55 with a stator adapted to permit air inlet opposite this last flange.
21. In a rotary fluid pump, a stator having an axially-directed cylindrical flange, an end wall secured to said flange and having 60 end ports therein and an axially ex-
- tending flange about the ports in combination with a rotor and a series of vanes on the rotor having end walls sealing against the last named flange.
22. In a rotary fluid pump, a stator having an axially directed cylindrical flange, an end wall secured to said flange and having end ports therein and a rotor having vanes extending toward said ports. 65
23. In a rotary fluid pump, a stator having an axially directed cylindrical flange, an end wall secured to said flange and having end ports therein and a rotor having vanes extending toward said ports, carrying part of an end wall between adjoining vanes 70 and utilizing the end wall on the flange for the remaining end wall between the vanes.
24. In a multistage pump, a rotor, oppositely directed vanes on opposite faces thereof, some on each face being arranged 75 at different distances from the center, in combination with a stator, oppositely directed cylindrical partitions carried by the stator to coöperate with the rotor vanes and walls upon the stator forming a passage 80 from the outer surface of the outer partition of one part to the interior of the inner partition of the other.
25. In a multistage pump, a stator, partitions thereon of cylindrical form in two sets 85 extending toward each other, walls forming communication between the outside of one set and the inside of the other, a rotor mounted between the two sets and oppositely facing vanes upon the rotor coöperating 90 with the two sets of partitions.
26. In a multistage pump, a rotor, blades thereon in sets extending away from each other axially on opposite sides of the rotor and some on each side at different distances 100 from the axis, in combination with a stator, partitions on the stator coöperating with the rotor vanes to form two axially-staged fluid pumps and walls connecting the two pumps in series. 105
27. In a multistage pump, an outer casing, a stator structure therein having a plurality of circular partitions ported at intervals and arranged in two sets upon opposite faces of a common support, both radially 110 extending, in combination with a rotor spider dividing the air on one side of the rotor from the air on the outer side thereof, vanes on the rotor extending axially between the successive partitions and walls directing the fluid from the outside of one set of partitions to the inside of the other set thereof. 115

THOMAS W. GREEN.
